UNITED STATES PATENT OFFICE.

ALEXANDER S. PRECINAUSKAS, OF WAUKEGAN, ILLINOIS.

GAME.

1,373,448.

Specification of Letters Patent.

Patented Apr. 5, 1921.

Application filed May 3, 1920. Serial No. 378,382.

To all whom it may concern:

Be it known that I, ALEXANDER S. PRECINAUSKAS, a citizen of Lithuania, residing at Waukegan, in the county of Lake and State 5 of Illinois, have invented certain new and useful Improvements in Games, of which the following is a specification.

My invention relates in general to games, and more particularly to a game of the type 10 which comprises a board the surface of which is divided into spaces upon which men are moved.

The primary object of my invention is to provide a game somewhat similar to 15 checkers, but which may be played by two or more persons.

A further object of my invention is to provide a game which will be simple to understand but which will afford entertainment and amusement to the players. 20

My invention will be more fully disclosed hereinafter with reference to the accompanying drawing, in which the same is illustrated as embodied in a convenient and practical form, and in which—

Figure 1 is a plan view of the board;

Fig. 2 is a plan view of one of the men; and

Fig. 3 is a plan view of the reverse side 30 of one of the men.

Reference letter A indicates a board, which may be made of any suitable material, such, for instance, as paste-board or wood. The board A is triangular in shape and the 35 upper surface thereof is divided into triangular spaces, alternate spaces being of one color and intermediate spaces of a distinguishing color. The alternate spaces b may, for instance, be black, and the intermediate spaces a, white. The corner spaces, 40 B, C and D, are colored differently from the other spaces. For instance, each corner space might comprise a border of the same color as the spaces b and a central portion of the same color as the intermediate spaces a. The spaces are arranged in parallel rows 45 extending inwardly from the several corners. b¹ indicates the first row of spaces parallel to the corner space B, while b², b³ and b⁴ designate successive rows of spaces parallel to the corner space B and extending inwardly of the board. c¹, c², c³ and c⁴ indicate rows of spaces extending inwardly of and parallel to the corner space C. d¹, d², 55 d³ and d⁴ indicate the rows of spaces parallel

to and extending inwardly from the corner space D.

The inner rows of spaces b⁴, c⁴ and d⁴ are differently designated from the other rows, as by means of lines e¹, e² and e³, respectively. The rows b⁴, c⁴ and d⁴ in which the said lines e¹, e² and e³ respectively occur are known as "neutral" spaces.

Sets of men are provided which preferably substantially conform to the shapes of the spaces. One of such men is shown in Figs. 2 and 3. The opposite surfaces of the men are differently colored. For instance, one surface may correspond to the corner spaces on the board, as shown in Fig. 2, while the opposite surface may be of a solid color corresponding to the color of the spaces b on the board, as shown in Fig. 3. Three sets of men are provided, each set being distinguishable in color from the other sets.

The game is played as follows:

When three persons are playing, the three sets of men, preferably ten men to a set, are placed upon the board. The person 80 who is playing from the corner B arranges his men on the corner space and on the spaces b in the rows b¹, b² and b³. The sets of men of the persons who play from the corners C and D are similarly arranged upon 85 the board; i. e., the men of each player are located upon the corner space and upon the alternate spaces b located in the three parallel rows of spaces extending inwardly from the corner.

The players move their men in regular turn. The object of each player is to move his men to the corner space of either of his opponents, and in doing so he may jump one of his men over the man of either opponent on spaces b in a direction toward the corners of either of his opponents, provided that there are unoccupied spaces b between the opponent's men in the direction he is moving his man. It is not permissible to 100 move the men backward, i. e., toward the corner of the board from which they are initially played; but after a man has reached the corner space of either of the opponents, it is turned over so as to indicate that it 105 may then move in any direction and may at a single move jump over the opponents' men located in any space along any of the rows of spaces. A man occupying a space in the rows designated as neutral by the letters 110

e^1 , e^2 and e^3 may not, however, be jumped by an opponent whose man is also on the same neutral row.

When only two persons are playing, their 5 men may be moved toward the vacant corner, but without attaining the same privileges thereby as when reaching the opponent's corner space.

Whether two or more persons play, the 10 winner is the player who has jumped all of his opponent's men or has the same blocked, and still has one or more of his own men left on the board.

In playing the game it is possible for two 15 players to play against a third, in which event each of the two would coöperate with his partner to jump or block all of the men of the third player. Where two play against a third, the moves of each of the two would 20 be toward the corner space of the third and neither of the partners would play toward the corner space of the other.

From the foregoing description it will be observed that I have invented a game which 25 is simple and easy to understand, but which at the same time is capable of such a variety of moves as to afford amusement and entertainment to the players.

I claim:

30 1. A game comprising a triangular board having a triangular space at each corner and parallel rows of triangular spaces extending inwardly from the corners, the corner spaces having a different appearance from the 35 other spaces, and the alternate spaces in the rows being of a color contrasting with the color of the intermediate spaces in the rows,

and a plurality of sets of reversible men, the men of each set being distinguishable from those of the other sets and one side of 40 each man corresponding in appearance to the corner spaces on the board.

2. A game comprising a triangular board having on the surface thereof spaces arranged in series of parallel rows, one series extending 45 inwardly from each corner of the board, alternate spaces being of a color contrasting with the color of the intermediate spaces, and the spaces in one row in each series being distinctively marked, and a plurality 50 of sets of men, the men of each set being of a different color from those of the other sets, and the number of men in each set corresponding to the number of alternate spaces in a predetermined number of rows. 55

3. A game comprising a triangular board having the surface thereof divided into a triangular space at each corner and parallel rows of triangular spaces extending inwardly from the corners, alternate spaces 60 being of a color contrasting with the color of the intermediate spaces, the corner spaces having a different appearance from the other spaces and the spaces in one row in each series being distinctively marked, and a 65 plurality of sets of reversible men, the men in each set being colored differently from those of the other sets, and one side of each man corresponding in appearance to the corner spaces on the board.

Signed at Chicago, Illinois, this 28th day of April, 1920.

ALEXANDER S. PRECINAUSKAS.
